FIG. 1.

Patented May 4, 1920.

FIG. 2.

Charles J. Messer, ^{INVENTOR}
BY
Howard P. Dawson, ^{ATTORNEY.}

UNITED STATES PATENT OFFICE.

CHARLES J. MESSEY, OF SYRACUSE, NEW YORK.

DESIGN FOR A CANDLE.

55,066.

Specification for Design.

Patented May 4, 1920.

Application filed April 5, 1918. Serial No. 226,958. Term of patent 14 years.

To all whom it may concern:

Be it known that I, CHARLES J. MESSEY, a citizen of the United States, residing at the city of Syracuse, in the county of Onondaga and State of New York, have invented a new, original, and ornamental Design for Candles, of which the following is a specification, reference being had to the accompanying drawing, forming part thereof.

Figure 1 is a top plan and Fig. 2 a side elevation of a candle showing my new design.

As made by me, the material of which the body —1— of the candle is formed is of

substantially a corn color, while the husks or strips —2— covering parts of the rows of corn are preferably of greenish color and the base —3—, as well as the contracted neck portion —4—, is of some suitable color, such as dark green, etc.

What I claim is:

The ornamental design for a candle as shown and described.

CHARLES J. MESSEY.
